UNITED STATES PATENT OFFICE.

MAJOR J. ROBINSON, OF LOS ANGELES, CALIFORNIA.

ROTARY ENGINE.

SPECIFICATION forming part of Letters Patent No. 683,987, dated October 8, 1901.

Application filed July 10, 1901. Serial No. 67,743. (No model.)

To all whom it may concern:

Be it known that I, MAJOR J. ROBINSON, a citizen of the United States, residing at Los Angeles, in the county of Los Angeles and State of California, have invented a new and useful Rotary Engine, of which the following is a specification.

My invention relates to engines of the rotary type, and particularly of the class where-
10 in the rotary element receives its motion from the thrust incident to the linear movement of a reciprocating piston; and the special ob-
ject of my invention is to provide a single-
acting device of this class having a minimum
15 number of operating elements and embody-
ing a construction wherein the revoluble ele-
ment may perform the dual function of a cyl-
inder and a power-transmitting wheel, pul-
ley, or gear.

20 Further objects and advantages of the in-
vention will appear in the following descrip-
tion when considered in connection with the
accompanying drawings, wherein similar ref-
erence characters represent corresponding
25 parts, and the novel features thereof will be
particularly pointed out in the appended
claims, it being understood that various
changes in the form, proportion, size, and
minor details of construction may be resorted
30 to without departing from the spirit or sacri-
ficing any of the advantages of the invention.

In the drawings, Figure 1 is a sectional
view of an engine constructed in accordance
35 with my invention. Fig. 2 is a similar view
showing the operating-piston in a different
position—namely, at the end of the power-
stroke. Fig. 3 is an end view of the rotary
cylinder. Fig. 4 is a vertical sectional view
40 on the plane indicated by the line 4-4 of Fig.
2. Fig. 5 is a detail view of the cylinder-
spindle.

Arranged at one end of a suitable base 1 is
a pedestal or column 2, provided with a bearing
3, in which is axially arranged a spindle
45 4. A cylinder 5 is provided with a tubular
journal or trunnion 6, the bore of which is
continued through the body portion of the
cylinder and is of such a diameter as to snugly
but revolvably fit said spindle, the latter be-
50 ing stationary. The cylinder consists of a
block centrally disposed with relation to the
sleeve 3 and with relation to the spindle 4,

and it is provided eccentrically with a piston
guide or chamber 7, located wholly at one
side of the spindle and having a reciproca- 55
tory piston-head 8 located therein. In the
construction illustrated one end of the piston-
chamber is open, and it is designed to apply
steam to only one side of the piston, and thus
adapt it for only one direct power-stroke 60
due to the expansion of the motive agent
which is admitted to the piston-chamber
through a feed-channel 9, formed in the spin-
dle and having a port 10, which is adapted
in one position of the cylinder to register 65
with a cylinder-inlet port 11, located in the
wall of the piston-chamber. Said ports are
shown in registration in Fig. 1. Also pref-
erably formed in the spindle 4 is an exhaust-
channel 12, with which said piston-chamber 70
port 11 is adapted to communicate in another
position of the cylinder, as indicated in Fig.
2, the sleeve 6, which performs the function
in the preferred embodiment of my inven-
tion of a valve or cut-off, having an exhaust- 75
port 13 to register with the other end of the
exhaust-channel 12 when said piston-cham-
ber port is in position to permit the contents
of the piston-chamber to exhaust. Obviously
the piston is adapted to receive a secondary 80
or return impulse by reason of the exhaust
and condensation of the motive agent, par-
ticularly if the exhaust-pipe 14 is connected
with a condenser, as may be desirable under
certain circumstances, specific illustration of 85
such an arrangement being unnecessary, how-
ever, because of the fact that it is well known
in the art. The motive agent, whether steam
or other fluid, may be conveyed to the feed-
channel 9 by means of the supply-pipe 15. 90

Pivots connected with the piston-head, pre-
ferably by a ball-and-socket or other prac-
tical antifriction and universal bearing 16, is
a thrust member or pitman 17, having its
other end correspondingly mounted, as at 18, 95
upon a thrust-block or step 19, which in the
construction illustrated consists of an en-
largement at the opposite end of the base 1
from the said column 2. The relation be-
tween the parts is such that the outer or, as 100
I will term it hereinafter, the "stationary"
end of the thrust member is permanently be-
low the plane of the movable end of said
thrust member, or, in other words, is below

the plane of said movable end of the thrust member when the latter is at the limit of its downward movement. Hence when the piston is at the limit of its inward stroke the application of pressure to its inner face causes the thrust member to exert a downward thrust on the step 19 and a consequent upward thrust on that portion of the cylinder which is adjacent to the piston-head. Moreover, except when the thrust member is located exactly in the vertical plane of the axis of the cylinder the application of motive agent to the piston causes a lateral thrust to be applied to the cylinder. Hence even without a secondary impulse being applied to the piston by the suction due to the exhaust of the steam or other motive agent from the piston-chamber the effect of the thrust due to the application of the steam would carry the cylinder through one-half of a revolution, and at the end of the direct stroke of the piston the momentum of the cylinder would continue the rotation until the parts were in position to receive a second impulse of the motive agent. In practice, however, the ports for admitting and exhausting motive agent may be so disposed as to be brought into operative relation alternately, and the inlet feed-port may even be so controlled as to cut off the influx of motive agent and allow for the operation of the parts for a portion of the stroke by the expansion of the motive agent. These details of construction and arrangement, however, form no part of my present invention, which contemplates the operation of the rotary cylinder by means of a single-acting reciprocating piston, the valve mechanism whereby the inlet and exhaust of the motive agent are controlled being disposed axially of the cylinder to leave the cylinder with an unobstructed exterior surface, whereby, if made of a suitable contour, the cylinder may be used as a power-transmitting medium, such as a drive pulley or wheel or a gear or its equivalent.

Having described the invention, what is claimed is—

1. An engine having a revoluble cylinder provided with an eccentric piston-chamber, a reciprocating piston mounted therein, a thrust member connected with the piston and having its other end provided with a bearing on a stationary step and valve mechanism for controlling the inlet and exhaust of motive agent. 50

2. An engine having a revoluble cylinder provided with an eccentric piston-chamber, a piston operating therein, a stationary step, a thrust member or pitman having its extremities universally mounted respectively upon said step and upon the piston, and valve mechanism for controlling the inlet and exhaust of motive agent. 55

3. A revoluble power-transmitting element having a piston-chamber disposed eccentrically thereof and parallel with its axis of rotation, a piston, a thrust member connecting said piston with an exterior fixed object, and valve mechanism for controlling the admission and exhaust of motive agent. 60

4. A revoluble cylinder having an eccentric piston-chamber, and axial stationary spindle having feed and exhaust channels therein, a port in communication with the piston-chamber, for alternate registration with said channels, a piston, and a thrust member having one end fixed to an outside stationary object. 65

5. The combination of a rotary cylinder having an eccentric piston-chamber and a concentric sleeve provided with feed and exhaust ports, a stationary spindle located within said sleeve and having inlet and exhaust channels, a piston, and a thrust member connecting said piston with an exterior fixed object. 70

In testimony that I claim the foregoing as my own I have hereto affixed my signature in the presence of two witnesses.

MAJOR J. ROBINSON.
